(57) CLAIM

The ornamental design for a card slab sleeve as shown and described.

DESCRIPTION

FIG. 1 is a front view showing my new design for a card slab sleeve.

FIG. 2 is a rear view of the card slab sleeve of FIG. 1.

FIG. 3 is a left side view of the card slab sleeve of FIG. 1.

FIG. 4 is a right side view of the card slab sleeve of FIG. 1.

FIG. 5 is a top view of the card slab sleeve of FIG. 1.

FIG. 6 is a bottom view of the card slab sleeve of FIG. 1.

FIG. 7 is a plan view of the outer side of the card slab sleeve of FIG. 1, shown in a preform configuration.

FIG. 8 is a plan view of the inner side of the card slab sleeve of FIG. 1, shown in a preform configuration.

FIG. 9 is a front view of the card slab sleeve of FIG. 1, depicting how the card slab sleeve would appear containing a card slab.

FIG. 10 is a rear view of the card slab sleeve of FIG. 1, depicting how the card slab sleeve would appear containing a card slab.

FIG. 11 is a left side view of the card slab sleeve of FIG. 1, depicting how the card slab sleeve would appear containing a card slab.

FIG. 12 is a right side view of the card slab sleeve of FIG. 1, depicting how the card slab sleeve would appear containing a card slab.

FIG. 13 is a top view of the card slab sleeve of FIG. 1, depicting how the card slab sleeve would appear containing a card slab; and,

FIG. 14 is a bottom view of the card slab sleeve of FIG. 1, depicting how the card slab sleeve would appear containing a card slab.

The broken lines shown throughout the figures are included for the purposes of illustrating environment and unclaimed features and form no part of the claimed design. The card slab sleeve of FIGS. 9-14 depict how the card slab sleeve would appear containing a collector card slab which would be viewable through the transparent window portions of the card slab sleeve in the front and rear views of FIGS. 9 and 10. The collector card slab, contained within the card slab sleeve in FIGS. 9 and 10, is shown with broken or dashed lines and with an irregularly dotted area within broken lines, and is included for the purposes of illustrating environment and forms no part of the claimed design. Horizontal folding lines are also shown in broken or dashed lines in FIGS. 7 and 8 and are for illustrating the location of folds and form no part of the claimed design.
